UNITED STATES PATENT OFFICE.

ARTHUR JAMES POSTANS, OF PUTNEY, ENGLAND.

CALCULATING-MACHINE.

No. 851,433.

Specification of Letters Patent.

Patented April 23, 1907.

Application filed March 12, 1906. Serial No. 305,651.

To all whom it may concern:

Be it known that I, ARTHUR JAMES POSTANS, a subject of the King of England, residing at Putney, in the county of Middlesex, England, have invented certain new and useful Improvements in Calculating-Machines, of which the following is a specification:

This invention relates to improvements in calculating machines, more especially those for casting up columns of figures, and has for its object to provide a machine in which two or more registering drums may be independently operated by keys allotted to each, without interfering with the "carrying-on" mechanism operating between them to pass the total of, say, the units drum on to the tens drum.

The invention has further reference to a particular construction of "carrying-on" mechanism which may be more positive than those at present in use, and a further feature of the invention has reference to the mechanism for bringing all the drums or indicators to zero.

In a machine in which units keys only are employed, all that is necessary for operating the machine is to drive the units drum by means of the keys and "carry-on" by any suitable counting mechanism from the units to the tens, hundreds and other drums. If, however, it is desired to employ tens keys, hundreds keys, etc., in addition to the units keys, it necessary that the tens and hundreds drums must be operated independently by their respective keys. At the same time the units drum must be able to "carry-on" to the tens and the tens to the hundreds, etc., without interfering with the independent operation of these drums by their respective keys. For this purpose it is necessary that the "carrying-on" mechanism shall only come into operation at the moment when the units, or other drum passing its total on, is turning from the 9 to the zero, and such mechanism must be automatically disconnected directly after operation.

The whole mechanism is enclosed in a suitable casing having one or more apertures with which the numbers on the registering drums are made to register in turn to indicate the total as is usual with machines of this class.

In the accompanying drawings:—Figure 1 is a perspective view of the zeroing mechanism constructed according to this invention,

and also shows a known method of operating the units drum; Fig. 2 is a perspective view showing a form of "carrying-on" mechanism constructed according to this invention; 6c Fig. 3 is a perspective view of the operating mechanism for the tens drum; Fig. 4 is a horizontal section through the end of the zeroing shaft shown in Fig. 1; and Fig. 5 is an end elevation of a modified form of "carrying-on" mechanism constructed according to this invention.

Like letters indicate like parts throughout the drawings.

The machine shown in the drawings is for adding only, and is of that type in which a transverse shaft A, normally stationary, is employed for carrying the registering drums which may vary in number according to the value of the computations intended to be effected by the machine. The units drum B is shown in Fig. 2 but in Fig. 1 it is removed in order that the operating mechanism may be clearly shown. Fast to the units drum is a toothed wheel B¹ free to rotate on the shaft A, and it is by imparting movement to this wheel that the drum is rotated.

Beside the wheel B¹ a second toothed wheel C is mounted and carries an arm C¹ having pivoted to it a spring-controlled pawl C² 85 which engages the teeth of the wheel B¹. Engaging the wheel C is a tooth rack D free to swing upon a shaft D¹ and normally held in the position shown in the drawings by a spring hereinafter referred to. The rack is 90 secured to a rocking frame D² with one end of which a series of key levers D³ engage. The keys are not shown in the drawings, but each lever D³ has an extension D⁴ which projects outside the casing X, in which the whole 95 mechanism may be enclosed, and carries the key, as will be readily understood. Each key lever also has an arm D⁵ connected to some part of the frame of the machine by a spring D⁶ which returns the key to the raised 100 position after it has been depressed. The rack D is normally maintained in the position shown in the drawing by a spring D⁷ operating upon the rocking frame D².

When the units key is depressed, the frame 105 D² is rocked and the toothed rack D moved in the direction indicated by the arrow, so that the wheel C is rotated and the arm C¹ drawn backward. During this movement the pawl C² slides over the teeth of the wheel B¹. The amount of this forward movement varies according to the value of the key de-

pressed and when the key is released the arm C returns under the action of the spring D⁷ and carries with it the wheel B¹ and thus the units drum B. Each tooth on the wheel B¹ corresponds to one of the numbers on the units drum, so that the drum will be rotated through an angle corresponding to one, two, or more units, according to the number of teeth over which the pawl C² has been withdrawn. Any convenient mechanism may be employed for varying the amount of displacement of the rack D according to the value of the key depressed.

A spring-controlled pawl E prevents backward rotation of the drum B and a second pawl E¹ is pivoted to a shaft E² and controlled by a spring E³, which normally tends to keep the pawl out of engagement with the wheel B¹. On the arm C¹ a pin C⁴ is mounted which at the end of the movement of the arm strikes the pawl E¹ and presses it down into engagement with the wheel B¹ to prevent overrunning of the drum, but as soon as the arm moves away from the pawl E¹, the latter rises and leaves the wheel B¹ free to rotate in the advance direction.

All the mechanism so far described with reference to the drawings is of known construction and forms no part of the present invention but is introduced to make clear the operation of the parts to which this invention refers. Such mechanism has, however, so far been only employed for operating the units drum, but according to this invention similar mechanism is employed to independently operate the tens drum and may be further applied to the hundreds and other drums, if desired.

The tens drums F, shown in Fig. 3, is mounted beside the units drum and has fast upon it a wheel F¹ corresponding to the wheel B¹ of the units drum. Beside this, and free upon the shaft A, is a toothed wheel G corresponding to the wheel C of the units drum, and this carries an arm G¹ having a spring-controlled pawl G² for the purpose of operating the wheel F¹ in precisely the same manner as already described in connection with the units drum. In Fig. 2 the wheel G is shown in place beside the units drum, but the arm G¹ attached to this wheel is omitted for the sake of clearness. The wheel G is engaged by a rack H operated by the tens keys in any convenient manner, such, for instance, as that described with reference to the rack D. The rack H is spring-controlled, either through the key mechanism or by other means, and normally is maintained in such position that the pin G³ on the arm G corresponding to the pin C³ on the arm C bears against the pawl for preventing overrunning of the drum F but when the drum is to be operated the rack is displaced and rotates the wheel G first in one direction and then in the other.

To effect the "carrying-on" from the drum B to the drum F a cam J is made fast to the side of the units drum B and an arm K is pivoted to a shaft at the rear of the shaft A, conveniently the shaft E² already referred to as carrying the pawls E E¹. The arm K extends over the cam J and carries a roller K¹ which rides upon the periphery of the cam and at the required moment drops over a step J¹ of the cam. Pivoted to the arm K at K² is a finger K³ which depends at the side of the cam J and is controlled by a spring K⁴ so that normally it is kept against a stop K⁵ on the arm K. The free end of the finger K³ has a claw or detent K⁶ disposed in the same plane as the wheel G but the spring K⁴ by normally retaining the finger against the stop K⁵ holds the detent end K⁶ of the finger clear of the wheel G, whatever position may be occupied by the arm K.

It will be seen that as the units drum B rotates the cam J is carried around so that the arm K is gradually raised until its roller K¹ falling over the step J¹ allows the arm to be drawn down to its lowest position by a controlling spring K⁷.

As already stated, the finger K³, if left to itself, would fall clear of the wheel G when the arm drops in this manner, but the cam has a pin J² which lies in the path of a lateral projection or striking plate K⁸ on the finger K³. It results therefore that as the step J¹ on the cam J approaches the roller K¹ of the arm K, the pin J² is brought against the striking plate K⁸ on the finger K³ and as it advances carries the finger in towards the wheel G. By the time the roller K¹ drops over the step J¹ of the cam, the detent K⁶ of the finger K³ has been brought into engagement with the teeth of the wheel G so that as the arm K drops, the detent carries the wheel backward. This movement displaces the toothed rack H against the action of its returning spring, but, immediately the movement of the arm K is completed, the detent K⁶ is withdrawn from the wheel G which allows the wheel to be returned by the rack to its normal position of rest. The drop of the arm K is sufficient to carry the wheel G round such a distance that the pawl arm G¹ is rotated through an angle sufficient to bring the pawl G² over the next tooth of the tens drum F, and consequently when the wheel is returned by the rack H, the drum is advanced one tooth, thus increasing the record total the desired amount.

The release of the detent K⁶ from the wheel G is effected by making the striking plate K⁸ of such length that when the arm K is dropped to its lowest position the whole of the plate K⁸ lies below the pin J². The pin is thus free to continue its forward movement with the cam, and the finger K³ swings out clear of the wheel G under the action of its spring K⁴.

If a key be depressed to advance the units

drum a distance equal to, say, four additional units, whereas a movement equal to only one unit is sufficient to bring the step J^1 of the cam J beneath the roller K^1 for recording another ten on the tens drum, it is desirable to provide means to prevent the rapid movement of the drum B and consequently the cam J from bringing the pin J^2 forcibly against the projection K^2 on the finger K^2 before the arm K has had time to drop. It will be seen that if this occurred the mechanism would become locked, as further advance of the units drum would be prevented by the pin J^2 and the arm K would be unable to drop for the purpose of operating the wheel G owing to the pressure of the pin. The means provided for this purpose comprise a catch K^3 on the arm K which when the arm is in the raised position lies in the path of a pin J^3 on the cam J . The distance between the pin J^3 and catch K^3 is so gauged that the pin will be brought against the catch and momentarily lock the drum B at the instant the roller K^1 passes over the step J^1 of the cam. This ensures that the arm K shall have time to drop before any further advance of the pin J^2 can take place. Immediately the arm has dropped, the pin J^2 is free to advance, and the catch K^3 , having dropped with it, no longer stops the advance of the pin J^3 , so that the drum B continues its rotation apparently without check; it will be appreciated that this arrangement ensures a positive action of the parts.

By leaving the wheel G of the tens drum F entirely free of the "carrying-on" mechanism except at the moment of "carrying-on", the drum F can always be itself operated directly by the tens keys allotted thereto.

It will be seen that the cam J , as shown in the drawings, is a double cam having two steps J^1 J^4 respectively, and each half of the cam has a pin corresponding to the pin J^3 and another corresponding to the pin J^2 . This however is mere duplication and is introduced because it is convenient to provide a double set of figures on the drum B so that at each half revolution the units drum completes its record and passes from 9 to zero.

Another construction of "carrying-on" mechanism, applicable between the units and tens drums, and adapted to leave the latter free for independent operation, is shown in end elevation in Fig. 5. In this form of apparatus the operating mechanism for the tens drum comprises, as before, a spring-controlled toothed rack L , corresponding to the rack H , and a toothed wheel L^1 gearing therewith and corresponding to the wheel G ; the wheel L carries a pawl arm similar to the arm G^1 , but as this has already been fully described with reference to Figs. 1 to 3, it is unnecessary to again detail these parts, and for clearness they are omitted from the drawing. The units drum further carries a double cam M ,

corresponding to the cam J , having steps M^1 , but in place of pins J^2 , segmental stops M^2 are provided. A pivoted arm N controlled by a spring N^1 extends over the cam M and carries a roller N^2 which rests upon the periphery of the cam, these parts corresponding to the arm K and roller K^1 . In place, however, of the finger K^3 , a wedge-shaped finger N^3 is pivoted to the arm and lies between the pin L^1 on an extension or tail-piece L^3 of the rack L and the segments M^2 on the cam M . So long as neither of the segments M^2 lies between the pin L^1 and the centre of the shaft A^1 carrying the mechanism, the wedge N^3 slides freely upon the pin L^1 of the rack L , as the arm N rises, but just before the roller N^2 drops over one of the steps M^1 on the cam, one of the segments M^2 is brought into position immediately behind the wedge N^3 , so that, as the arm N descends, the wedge, being unable to move towards the shaft A^1 , forces the pin L^1 in a direction away from the shaft. The wedge is of such width that it displaces the pin, and consequently the rack L a sufficient distance to move the pawl arm carried by the wheel L^1 back one tooth, but when the arm N has reached its lowest position, the largest part of the wedge has passed below the pin L^1 so that the rack L is released and owing to its spring-control returns the wheel L^1 and thus advances the tens drum the required amount, the pin L^1 now lies above the shoulder N^4 on the wedge N^3 .

Obviously pins may be utilized in place of the segments M^2 , but the segments make the operation positive in the same manner as the catch K^3 and pin J^3 render the device previously described positive, that is to say, with a pin only it might be possible to rotate the units drum so rapidly that the pin would pass the wedge before the latter had dropped, whereas the segments may be made of such length that the complete movement of the wedge is ensured before the segment passes.

As already mentioned, any number of drums may be mounted on the shaft A with either the "carrying-on" mechanism described, or any suitable form of "carrying-on" mechanism, disposed between them, and, with all machines of this kind, it is desirable to return the whole of the drums to zero simultaneously with as little labour as possible. For this purpose the shaft A has heretofore been made movable endwise and provided with pins A^2 adapted to engage pins A^3 on the drums. Each drum is provided with one of the pins A^3 , and a pin A^2 is also allotted to each drum, but when the shaft is in the normal position the pins A^2 lie clear of the pins A^3 . By movement of the shaft endwise, however, all of the pins A^2 are simultaneously brought into the path of their respective pins A^3 so that by one rotation of the shaft the pins A^3 may be all brought

- into line, whatever position they may previously occupy. The shaft is provided with a handle A^4 for rotating it and a pin A^5 adapted to engage an orifice A^6 in the casing. 5 The shaft A is spring-controlled and the orifice A^6 so situated that as soon as the pin A^5 is brought into line with it the shaft A is returned under the action of its spring and the drums are all left at the zero position. 10 Before, however, it is possible to return the drums the pawls E^1 must be released, and heretofore it has been necessary to rock the operating racks slightly forward by a separately operated lever so that the pawl arms C^1 might be advanced sufficiently to allow the arms E^1 to rise. The object of this part of the present invention is to render these two operations simultaneous. For this purpose a head O is mounted on that end of the 15 shaft A remote from the handle A^4 and the underside of the head is bevelled to constitute a cam, as shown at O^1 , and against this bevelled portion the free end of an arm O^2 bears. The arm O^2 is carried by the shaft D^1 and this shaft has a short arm O^3 having a laterally projecting pin O^4 . The pin lies in the path of a stop O^5 on one arm of the rocking frame D^2 with which the racks D and H referred to are connected. The spring for 20 controlling the shaft A is shown at A^7 and bears at one end against the casing X in which the mechanism is enclosed, and at the other end against the interior of the head O which is hollowed to receive the 25 spring.
- The operation of the zeroing mechanism is as follows: The head O is pushed to the left against the action of the spring A^7 so that the shaft is moved endwise and the pin A^5 displaced from the orifice A^6 in the wall of the casing. A slight rotation of the shaft A by means of the handle A^4 then carries the pin A^5 out of line with the orifice A^6 so that the shaft cannot return under the action of 30 its spring until it has been rotated through the desired angle unless of course it is moved backwards. The endwise displacement of the shaft A to the right causes the larger part of the cam or bevelled face O^1 of the head O to bear against the arm O^2 so that the free end of the arm is displaced further from the shaft A and consequently the shaft D to which the arm is attached is rocked in the same direction. This movement of the 35 shaft is communicated by the arm O^2 and pin O^4 to the stop O^5 and thus the rocking frame D^2 is slightly raised and the toothed racks D and H advanced a corresponding amount. The advance of the racks causes 40 a slight rotation of the toothed wheels C and G sufficient to carry the pins C^3 and G^3 away from the locking pawl E^1 and those corresponding to the same for the other drums. The drums are thus released and can now be 45 brought to zero by rotating the shaft A until
- the pin A^5 arriving opposite the orifice A^6 allows the shaft A to be returned to its normal position under the action of its spring when the arm O^2 also returns under the action of the springs controlling the racks 50 D and H .
- Only one orifice A^6 is shown in the drawings, but it will be understood that where recording drums are made to carry two sets of figures so that each half revolution gives 55 a total, each drum would carry two pins A^3 disposed diametrically opposite each other and two orifices A^6 would be provided in the casing so that zeroing would be effected by a half revolution of the shaft A . 80
- When zeroing the tens drum is arranged to be brought to 9 instead of 0 by the rotation of the shaft A as the "carrying-on" mechanism operates when the units drum comes to zero and thus automatically advances the tens drum to 0 as will be readily understood. 85
- What I claim as my invention and desire to secure by Letters Patent is:—
1. In a calculating machine the combination of a registering drum, keys operatively connected therewith for advancing the same, a second registering drum, a second set of keys operatively connected therewith for advancing the second drum independently of the first, a "carrying-on" finger disposed in proximity to the operating mechanism of the second drum, means operatively connected with the first drum for alternately advancing and withdrawing the "carrying-on" finger in a path in proximity to the operating mechanism of the second drum, and a member operatively connected with the first drum and adapted at the moment of "carrying-on" to be moved by the drum into co-operative position relatively to the "carrying-on" finger so that the finger as it advances imparts movement to the operating mechanism of the second drum, substantially as set forth. 90
  2. In a calculating machine the combination of a registering drum, keys operatively connected therewith for advancing the same, a second registering drum, a second set of keys operatively connected therewith for advancing the second drum independently of the first, a supporting member reciprocated by mechanism operatively connected with the first recording drum, a "carrying-on" finger yieldingly mounted on the supporting member and moving with the same in proximity to the operating mechanism of the second drum but being inoperative upon the said mechanism by reason of its yielding connection with the supporting member, and a member operatively connected with the first drum and adapted at the moment of "carrying-on" to be moved by the drum into co-operative position relatively to the "carrying-on" finger so that the yielding connection is overcome and the finger as it advances im- 100
  3. In a calculating machine the combination of a registering drum, keys operatively connected therewith for advancing the same, a second registering drum, a second set of keys operatively connected therewith for advancing the second drum independently of the first, a supporting member reciprocated by mechanism operatively connected with the first recording drum, a "carrying-on" finger yieldingly mounted on the supporting member and moving with the same in proximity to the operating mechanism of the second drum but being inoperative upon the said mechanism by reason of its yielding connection with the supporting member, and a member operatively connected with the first drum and adapted at the moment of "carrying-on" to be moved by the drum into co-operative position relatively to the "carrying-on" finger so that the yielding connection is overcome and the finger as it advances im- 110
  4. In a calculating machine the combination of a registering drum, keys operatively connected therewith for advancing the same, a second registering drum, a second set of keys operatively connected therewith for advancing the second drum independently of the first, a supporting member reciprocated by mechanism operatively connected with the first recording drum, a "carrying-on" finger yieldingly mounted on the supporting member and moving with the same in proximity to the operating mechanism of the second drum but being inoperative upon the said mechanism by reason of its yielding connection with the supporting member, and a member operatively connected with the first drum and adapted at the moment of "carrying-on" to be moved by the drum into co-operative position relatively to the "carrying-on" finger so that the yielding connection is overcome and the finger as it advances im- 120
  5. In a calculating machine the combination of a registering drum, keys operatively connected therewith for advancing the same, a second registering drum, a second set of keys operatively connected therewith for advancing the second drum independently of the first, a supporting member reciprocated by mechanism operatively connected with the first recording drum, a "carrying-on" finger yieldingly mounted on the supporting member and moving with the same in proximity to the operating mechanism of the second drum but being inoperative upon the said mechanism by reason of its yielding connection with the supporting member, and a member operatively connected with the first drum and adapted at the moment of "carrying-on" to be moved by the drum into co-operative position relatively to the "carrying-on" finger so that the yielding connection is overcome and the finger as it advances im- 130

parts movement to the operating mechanism of the second drum, substantially as set forth.

3. In a calculating machine the combination of a registering drum, keys operatively connected therewith for advancing the same, a second registering drum, a second set of keys operatively connected therewith for advancing the second drum independently of the first, a supporting member, a "carrying-on" finger pivoted thereto, operative connection between the supporting member and the first registering drum, whereby movement of that drum reciprocates the member and thus moves the finger backwards and forwards in a path in proximity to the mechanism of the second drum, means for limiting the movement of the finger about its pivot in a direction away from the operating mechanism of the second registering drum, a spring to retain the finger at the limit of its pivotal movement so that it is normally held clear of the said operating mechanism, and a member operatively connected with the first drum and adapted at the moment of "carrying-on" to be advanced by the drum against the finger so that the finger is carried forward against the action of its spring and brought into engagement with the operating mechanism of the second drum, substantially as set forth.

4. In a calculating machine the combination of a registering drum, keys operatively connected therewith for advancing the same, a second registering drum, a second set of keys operatively connected therewith for advancing the second drum independently of the first, "carrying-on" mechanism operative between the first and second drums for the purpose of passing on the total from the first drum to the second drum and means for momentarily automatically locking the first drum at the moment of "carrying-on", substantially as set forth.

5. In a calculating machine the combination of a registering drum, keys operatively connected therewith for advancing the same, a second registering drum, a second set of keys operatively connected therewith for advancing the second drum independently of the first, "carrying-on" mechanism operative between the two drums for the purpose of passing the total of the first drum on to the second, a stop operatively connected with the first drum and advanced as that drum advances, a catch operatively connected with the "carrying-on" mechanism and brought by the latter into the path of the stop at the moment of "carrying-on" so that further advance of the first drum is prevented until the completion of the "carrying-on", substantially as set forth.

6. In a calculating machine the combination of a registering drum, keys operatively connected therewith for advancing the same,

a second registering drum, a second set of keys operatively connected therewith for advancing the second drum independently of the first, a supporting member reciprocated by mechanism operatively connected with the first registering drum, a "carrying-on" finger pivoted to the supporting member but normally lying clear of the operating mechanism of the second drum, means operatively connected with the first drum for moving the finger into engagement with the mechanism of the second drum at the moment of "carrying-on" a catch on the supporting member, a stop operatively connected with the first drum so that it is advanced by that drum against the catch at the moment of "carrying-on" but afterwards released by the advance movement of the "carrying-on" mechanism, substantially as set forth.

7. In a calculating machine the combination of a registering drum, spring-controlled mechanism for advancing the same, keys operatively connected with such mechanism for the purpose of displacing it in a direction opposed to the action of the spring preparatory to operating the drum, a second registering drum, spring-controlled mechanism for operating this drum, a second set of keys operatively connected with such mechanism for the purpose of displacing the same in a direction opposed to the action of the spring preparatory to operating the drum, a "carrying-on" finger disposed in proximity to the operating mechanism of the second drum, means operatively connected with the first drum for alternately advancing and withdrawing the "carrying-on" finger in a path in proximity to the operating mechanism of the second drum, and a member operatively connected with the first drum and adapted at the moment of "carrying-on" to be moved by the drum into co-operative position relatively to the "carrying-on" finger so that the finger as it advances momentarily displaces the operating mechanism of the second drum against the action of the controlling spring, substantially as set forth.

8. In a calculating machine the combination of a shaft free to move endwise, a spring to normally maintain the shaft at one end of its travel, means for locking the shaft against rotation except when displaced endwise, a plurality of registering drums mounted free upon the shaft, a ratchet on each drum, a pawl engaging each ratchet to prevent rotation of the drums in one direction, a pivoted arm operatively connected with the pawl mechanism to simultaneously bring them out of engagement with their respective ratchets when moved in one direction, a frusta or cone-shaped head on the shaft, the axis of the frusta coinciding with that of the shaft, a spring-control for the pivoted arm so that the free end of the arm bears against the conical portion of the head, and means for automati-

ically engaging all of the drums with the shaft when the latter is moved endwise, such movement also oscillating the arm referred to by causing the larger part of the frusta to bear against the arm, substantially as set forth.

9. In a calculating machine the combination of a shaft free to move endwise, a spring to normally maintain the shaft at one end of its travel, means for locking the shaft against rotation except when displaced endwise, means to automatically prevent the return of the shaft after endwise displacement and partial rotation except it be rotated through a given angle, a plurality of recording drums mounted free upon the shaft, a ratchet on each drum, a pawl engaging each ratchet to prevent rotation of the drums in one direction, a pivoted arm operatively connected with the pawl mechanism to simultaneously

bring them out of engagement with their respective ratchets when moved in one direction, a frusta or cone-shaped head on the shaft, the axis of the frusta coinciding with that of the shaft, a spring-control for the pivoted arm so that the free end of the arm bears against the conical portion of the head, and means for automatically engaging all of the drums with the shaft when the latter is moved endwise, such movement also oscillating the arm referred to by causing the larger part of the frusta to bear against the arm, substantially as set forth.

In testimony whereof I have signed my name to this specification in the presence of two subscribing witnesses.
